UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BEDSPRING FABRIC.

Application filed April 22, 1921. Serial No. 463,631.

To all whom it may concern:

Be it known that I, CHARLES H. GAIL, a citizen of the United States, residing at Cincinnati, in the county of Hamilton and 5 State of Ohio, have invented certain new and useful Improvements in Bedspring Fabrics, of which the following is a specification.

My invention concerns features of novelty 10 in resilient or yielding, substantially-flat, metallic fabrics, such as are used in beds, couches, cushions, and the like, its primary purpose and leading object being the production of a structure of this kind which 15 will possess adequate elastic or cushioning characteristics, which will have sufficient strength to effectively sustain all ordinary loads imposed on it, which is composed of comparatively few parts easily assembled, 20 which is relatively inexpensive to manufacture, which has a pleasing and attractive appearance, and which may be shipped, if desired, separate from its supporting frame without becoming damaged or its several 25 parts becoming entangled with one another or detrimentally kinked, the structure nevertheless possessing a full degree of flexibility and pliability enabling it to be shipped or transported in small space.

30 To enable those skilled in this art to understand the manner of attainment of these and other desirable purposes or aims, I have illustrated a preferred embodiment of the invention in the accompanying drawing, 35 forming a part of this specification, to which reference should be had in connection with the following detailed description of the structure and throughout the several views of which like reference characters are 40 applied to the same parts.

In this drawing:

Figure 1 is a fragmentary plan view of the new fabric;

Fig. 2 is an enlarged vertical cross-section 45 on line 2—2 of Fig. 1;

Fig. 3 is an enlarged vertical longitudinal section on line 3—3 of Fig. 1; and Fig. 4 is a perspective view of one of the spring elements of the fabric.

50 In this drawing a very small portion only of the construction is illustrated, but it is sufficient to give an understanding of the whole.

The improved fabric comprises a number 55 of spaced, parallel, transverse rows of heli-

cal or coiled springs directly connected together end to end.

In the drawing, however, only two of such cross rows 10 and 11 of short coiled springs 12 have been shown, but in a full-size complete structure several of such rows would ordinarily be employed.

As is clearly depicted, all of these springs are alike, except those at the side margins of the fabric which may be slightly different but which need not here be illustrated since they may be of any appropriate form which will readily occur to those skilled in this industry.

Each spring 12 at one end has the terminal portion of the wire of which it is composed bent lengthwise the spring parallel to its axis and at the top of the end convolution to provide a short neck 13, and outwardly beyond this the wire is deformed or crooked at 14 to supply a portion or half of an eye or loop 15, the extreme end of the wire having a downturned hook 16.

At its opposite end the wire of each spring is similarly but reversely shaped to form a neck 17, a semi-eye 18, and a hook 19.

The ends of consecutive springs are connected together by applying the hook 16 of the one spring around the neck 17 of the next spring, and the hook 19 of the latter around the neck 13 of the former, thereby securely attaching the springs together end to end and forming the complete eye or loop 15 between them by its associated elements 14 and 18.

90 In this manner all of the springs of the several transverse rows are connected together providing between each pair of springs proper 12 one of the complete loops or eyes 15, those of the several cross rows 95 being in alignment lengthwise the fabric.

The longitudinal members of the fabric comprise wire links 20 desirably used in pairs, side by side, and each having downturned hooks 21 at its opposite ends.

100 These links extend from one row of springs to the next and their hook ends fit in the corresponding eyes or loops of such rows.

Thus two of these links hook over the part 18 of each eye or loop and another pair of links in line with the first pair hook over the complementary part 14 of the same eye or loop.

105 At the ends of the longitudinal rows of

wire links they are connected in any usual or customary manner, as by means of appropriate helical springs, to the end cross-bars of the frame, not shown.

- 5 Those acquainted with this art and its needs will readily understand that, by reason of the articulated or jointed characteristics of the fabric, and the liberal use of elastic cross springs, the structure as a whole comprises an effectively resilient cushion adapted for many useful purposes, such as in beds and couches.

10 By reason of the ready capacity of the cushion fabric to yield locally a body of uneven shape, such as that of the human form, is supported in an efficient and comfortable manner, as all parts of the fabric are more or less free to move or yield to conform themselves to the shape of the supported body.

15 Although coil springs are used they are so employed in the manner specified that the fabric has a comparatively smooth upper surface with no ends or projections likely to injure or damage the superposed mattress or other cushion.

20 It should be noted that the bent sections of successive springs unitedly or conjointly form complete eyes or loops between the springs in a plane substantially tangent to the top portions of such springs, whereby the bodies of the springs are positioned below the top practically-plane surface of the bed-spring fabric.

25 The invention is not limited and restricted to the precise and exact details of structure presented by way of illustration and description, these being capable of considerable change or modification without departure from the substance and essence of the invention as defined in the appended claims, and without the loss of any of its practical benefits and advantages.

30 For example, instead of using pairs of links side by side, single links of larger wire or strips of metal ribbon or bands may be employed if preferred.

35 Of course, the shapes of the eyes or loops between the springs are more or less immaterial and may be modified as occasion dictates.

40 The manner of attaching the ends of the springs together is subject to change if desired.

45 I claim:—

1. A bed-bottom fabric comprising in com-

bination, a plurality of spaced transverse rows of short coiled springs directly connected together end to end by terminal portions of the wires forming the springs, each such terminal portion at each end of each spring constituting a neck, a bent section forming a part of an eye beyond the neck, and an end hook beyond said bent section engaging the neck of the next spring, the bent sections of successive springs conjointly forming complete eyes between the springs, and spaced lengthwise rows of links each having hook ends engaging the corresponding eyes of two successive rows of transverse springs.

2. A bed-bottom fabric comprising in combination, a plurality of spaced transverse rows of short coiled springs directly connected together end to end by terminal portions of the wires forming the springs, each such terminal portion at each end of each spring constituting a neck, a bent section forming a part of an eye beyond the neck, and an end hook beyond said bent section engaging the neck of the next spring, the bent sections of successive springs conjointly forming complete eyes between the springs in a plane substantially tangent to the coiled springs, whereby the bodies of the springs lie below the top practically-plane surface of the fabric, and spaced lengthwise rows of links each having hook ends engaging the corresponding eyes of two successive rows of transverse springs.

3. A bed-bottom fabric comprising in combination, a plurality of spaced transverse rows of short horizontal helical springs directly connected together end to end with eyes between them each eye formed conjointly of terminal portions of the wires of which the adjacent springs are composed, and rows of elements disposed lengthwise the fabric engaging said eyes.

4. A bed-bottom fabric comprising in combination, a plurality of transverse rows of short coiled springs connected together end to end, each end of each spring being shaped to form an eye conjointly with the complementary portion of the bent end of the adjacent spring, and lengthwise rows of links with hook ends, each link extending only from one transverse row of springs to the next and hooking in the corresponding eyes thereof.

CHARLES H. GAIL.
